(Cl. D54—16)

To all whom it may concern:

Be it known that I, Irvin H. Blanchard, a citizen of the United States, residing at Wichita, Sedgwick County, State of Kansas, have invented a new, original, and ornamental Design for a Turnbuckle Wrench or the Like, of which the following is a specification, reference being had to the accompanying drawing, forming part thereof.

Fig. 1 is a plan view of a turnbuckle wrench, showing my new design.

Fig. 2 is an end view of the same.

Fig. 3 is an inside face view and

Fig. 4 is an outside face view of one of the wrench jaws.

Fig. 5 is an end view of one of the wrench jaws.

I claim:

The ornamental design for a turnbuckle wrench, substantially as shown.

IRVIN H. BLANCHARD.
